(57) **ABSTRACT**

A light source device, including a first light source, providing a first light beam in a first time period of a first period; and a second light source, providing a second light beam in a second time period of the first period, is provided. The first light beam and the second light beam have the same color temperature. The first light beam and the second light beam are emitted alternately in the first period, and a color rendering index of mixed light of the first light beam and the second light beam is greater than or equal to 85.

LIGHT SOURCE DEVICE AND DISPLAY DEVICE

CROSS-REFERENCE TO RELATED APPLICATION

This application is a continuation-in-part application of and claims the priority benefit of a prior application Ser. No. 17/565,495, filed on Dec. 30, 2021. The prior application Ser. No. 17/565,495 claims the priority benefit of U.S. Provisional Application No. 63/212,724, filed on Jun. 21, 2021, and Taiwan Application No. 110148157, filed on Dec. 22, 2021. The entirety of each of the above-mentioned patent applications is hereby incorporated by reference herein and made a part of this specification.

BACKGROUND

Technical Field

The disclosure relates to a light source device and a display device, and particularly relates to a light source device or a display device for giving visual stimulation with a fixed period/frequency.

Description of Related Art

Patients with Alzheimer's disease account for approximately 60% to 80% of the total number of patients with dementia. The pathological features of Alzheimer's disease include accumulation of abnormal proteins, such as amyloid plaque produced by β -amyloid between neurons, and neurofibrillary tangles formed by abnormal accumulation of tau protein in cells. The amyloid plaque may interfere with signals emitted by nerve synapses between the cells, and the neurofibrillary tangles may prevent nutrients from being transmitted in the cells, leading to cell death. Generally speaking, when glymphatic fluid, such as microglia and astrocyte, in the human body is functioning normally, the cerebrospinal fluid (CSF) may take away the accumulated abnormal proteins, and the abnormal proteins are metabolized by the liver. However, when the glymphatic fluid is not functioning normally, the accumulation of abnormal proteins in the brain cells cannot be eliminated, which eventually causes neurodegeneration to form Alzheimer's disease, causing dementia.

The current non-invasive stimulus signal for the treatment of Alzheimer's disease is to induce gamma brain waves by acousto-optic stimulation to activate the microglia, thereby eliminating the accumulation of abnormal proteins to alleviate cognitive decline. However, the current acousto-optic stimulus signal is extremely monotonous, long-term viewing or listening may easily cause fatigue or discomfort, and long-term application is difficult, which affects the willingness of the user to use.

SUMMARY

The disclosure provides a light source device, which can treat or alleviate diseases by giving visual stimulation with a specific period/frequency.

According to some embodiments of the disclosure, a light source device is provided, which includes a first light source, providing a first light beam in a first time period of a first period; and a second light source, providing a second light beam in a second time period of the first period. The first light beam and the second light beam are emitted alternately

2

in the first period, and a color rendering index of mixed light of the first light beam and the second light beam is greater than or equal to 85.

According to other embodiments of the disclosure, a display device is provided, which includes a light source device. The light source device includes a first light source, providing a first light beam in a first time period of a first period; and a second light source, providing a second light beam in a second time period of the first period. The first light beam and the second light beam are emitted alternately in the first period, and a color rendering index of mixed light of the first light beam and the second light beam is greater than or equal to 85.

According to some embodiments of the disclosure, a light source device is provided, which includes a first light source, providing a first light beam in a first time period of a first period; and a second light source, providing a second light beam in a second time period of the first period. The first light beam and the second light beam are emitted alternately in the first period, and the first light beam and the second light beam have a same color temperature.

Based on the above, the disclosure provides the light source device and the display device, which give visual stimulation with a fixed period/frequency to treat diseases by providing a light period of a combination of at least two different light. The more comfortable light stimulation combination can overcome the current issues of boring non-invasive stimulus signal and difficulty in long-term application, and can be used in lighting and display of daily life.

BRIEF DESCRIPTION OF THE DRAWINGS

FIG. 1 is a schematic diagram of a light source device according to some embodiments of the disclosure.

FIG. 2 to FIG. 6 are optical signal timing diagrams according to some embodiments of the disclosure.

FIG. 7 is an acousto-optic signal timing diagram according to some embodiments of the disclosure.

FIG. 8A to FIG. 8C are optical signal timing diagrams according to some embodiments of the disclosure.

FIG. 9 to FIG. 11 are optical signal timing diagrams according to some embodiments of the disclosure.

FIG. 12 is a schematic diagram of color coordinate configurations of the same color temperature defined by the American National Standards Institute.

FIG. 13A and FIG. 13B are spectral distributions with the same color temperature according to some embodiments of the disclosure.

FIG. 14A and FIG. 14B show a relationship between a color rendering index and an electroencephalography signal according to some embodiments of the disclosure.

FIG. 15A to FIG. 15B are optical signal timing diagrams according to some embodiments of the disclosure.

FIG. 16 is a schematic diagram of a display device according to some embodiments of the disclosure.

FIG. 17 is a schematic diagram of a display device according to some embodiments of the disclosure.

FIG. 18 is a schematic diagram of a light source device according to some embodiments of the disclosure.

FIG. 19-28 is an acousto-optic signal timing diagram according to some embodiments of the disclosure.

DETAILED DESCRIPTION OF DISCLOSED EMBODIMENTS

Please refer to the following embodiments and accompanying drawings in order to fully understand the disclosure,

but the disclosure can still be practiced in many different forms and should not be construed as being limited to the embodiments described herein. In the drawings, for the sake of clarity, components and relative sizes thereof may not be drawn according to actual scale.

FIG. 1 is a schematic diagram of a light source device according to some embodiments of the disclosure. FIG. 2 is an optical signal timing diagram according to some embodiments of the disclosure. Please refer to FIG. 1 and FIG. 2 at the same time. As shown in FIG. 1, a light source device 100 includes a first light source 110 and a second light source 120. According to some embodiments, the first light source 110 and the second light source 120 are array light emitting diodes or other elements that can emit light beams, and the disclosure is not limited thereto. The first light source 110 is configured to provide a first light beam L1, the second light source 120 is configured to provide a second light beam L2, and the first light beam L1 and the second light beam L2 are configured to be emitted alternately to provide light stimulation. As shown in FIG. 2, the first light source 110 is configured to provide a first light beam 201 in a first time period T11 of a first period T1, and the second light source 120 is configured to provide a second light beam 202 in a second time period T12 of the first period T1. The first time period T11 and the second time period T12 constitute the first period T1, and the first light beam 201 and the second light beam 202 are emitted alternately in the first period T1. According to some embodiments, a first frequency f1 corresponding to the first period T1 is 35-45 Hz, that is, $f1=1/T1=35-45$ Hz. According to some embodiments, the first frequency f1 corresponding to the first period T1 is 40 Hz, but the disclosure is not limited thereto. In the embodiment, the duration of the first time period T11 is equal to the duration of the second time period T12, that is, the first light beam 201 and the second light beam 202 have the same duty ratio, that is, $T11/T1=T12/T1$. In another embodiment, the first light beam 201 and the second light beam 202 may have different duty ratios.

In the embodiment, the first light beam 201 in the first time period T11 and the second light beam 202 in the second time period T12 are respectively continuous light beams. According to some embodiments, the wavelengths of the first light beam 201 and the second light beam 202 are between 380 nm and 1050 nm, and the disclosure is not limited thereto. According to some embodiments, the first light beam 201 and the second light beam 202 are monochromatic light, mixed light containing multiple monochromatic light, or full spectrum light, but not limited thereto.

In the embodiment, the first light beam 201 and the second light beam 202 have the same color temperature and the same spectrum. According to some embodiments, the color temperature of the first light beam 201 and the second light beam 202 is between 2000K to 7000K, but not limited thereto. According to some embodiments, the difference between the first light beam 201 and the second light beam 202 is that the first light beam 201 and the second light beam 202 have different light intensities, that is, the light intensity of the first light beam 201 may be greater than or less than the light intensity of the second light beam 202.

In the embodiment, a light intensity difference between the first light beam 201 and the second light beam 202 is less than a threshold. If the light intensity of the first light beam 201 is I1 and the light intensity of the second light beam 202 is I2, a light intensity difference D is defined as $D=|I1-I2|/I1+I2$. According to some embodiments, the light intensity difference D between the first light beam 201 and the second light beam 202 is less than 10%. In some embodiments, the

light intensity difference D between the first light beam 201 and the second light beam 202 is less than 5%. In some embodiments, the light intensity difference D between the first light beam 201 and the second light beam 202 is less than 2.5%.

When the first light beam 201 and the second light beam 202 are sequentially emitted in the first period T1, since the color temperature and the spectrum of the first light beam 201 and the second light beam 202 are the same, and there is only difference in light intensities, the first light beam 201 and the second light beam 202 emitted by the light source device 100 respectively flicker with different light intensities but the same first frequency f1 to provide light stimulation, and the mixed light of the first light beam 201 and the second light beam 202 has a high color rendering index (CRI), that is, $CRI \geq 85$. Since the difference between the light intensities of the first light beam 201 and the second light beam 202 is only less than the threshold, for example, the difference between the light intensities of the first light beam 201 and the second light beam 202 is less than 10% or less, for a patient to be treated, the received light intensity change is relatively small, which can reduce the burden on the eyes of the patient. By changing an irradiation period of the first light beam 201 and the second light beam 202 emitted by the first light source 110 and the second light source 120 in the light source device 100, light stimulation received by the patient may be adjusted, for example, when $f1=35-45$ Hz, thereby inducing gamma brain waves to activate microglia. In subsequent embodiments, various implementations will be explained one by one.

FIG. 3 is an optical signal timing diagram according to some embodiments of the disclosure. The optical signal timing diagram shown in FIG. 3 is similar to FIG. 2. The first light source 110 provides a first light beam 301 in the first time period T11 of the first period T1, and the second light source 120 is configured to provide a second light beam 302 in the second time period T12 of the first period T1. The light intensity difference between the first light beam 301 and the second light beam 302 is less than a threshold, for example, less than 10% or less.

The difference between FIG. 3 and FIG. 2 is that the first light beam 301 and the second light beam 302 have the same color temperature, but the second light beam 302 has a different spectrum from the first light beam 301. In other words, the first light beam 301 and the second light beam 302 have different wavelength compositions, and the first light beam 301 and the second light beam 302 are irradiated alternately in the first period T1. In another embodiment, the first light beam 301 and the second light beam 302 are mixed into light with a high color rendering index (for example, $CRI \geq 85$), and when $f1=35-45$ Hz, the patient is visually stimulated to induce gamma brain waves. Since the first light beam 301 and the second light beam 302 have the same color temperature but different spectra, the first light beam 301 and the second light beam 302 may have different light intensities for different usage purposes. In some embodiments, if the light source device 100 is used as a display, the first light beam 301 and the second light beam 302 may have the same light intensity to prevent the user from seeing a screen with changing brightness. In other embodiments, if the light source device 100 is used to provide illumination, the first light beam 301 and the second light beam 302 may have different light intensities, and the light intensity difference is less than a threshold, for example, less than 10% or less, so that the user receives light stimulation with changes in brightness.

FIG. 4 is an optical signal timing diagram according to some embodiments of the disclosure. The optical signal timing diagram shown in FIG. 4 is similar to FIG. 2. The first light source 110 provides a first light beam 401 in the first time period T11 of the first period T1, and the second light source 120 is configured to provide a second light beam 402 in the second time period T12 of the first period T1. The light intensity difference between the first light beam 401 and the second light beam 402 is less than a threshold, for example, less than 10% or less. In addition, the first light beam 401 and the second light beam 402 have the same color temperature and the same spectrum. In other embodiments, the first light beam 401 and the second light beam 402 have the same color temperature but different spectra.

The difference between FIG. 4 and FIG. 2 is that one of the first light beam 401 and the second light beam 402 is a continuous light beam, and the other one is a flicker light beam with a flicker frequency, which is also referred to as a pulse width modulation (PWM) beam. In the embodiment, the first light beam 401 is a continuous light beam in the first time period T11, the second light beam 402 is a flicker light beam with a flicker frequency in the second time period T12, and the first light beam 401 and the second light beam 402 are mixed into light with a high color rendering index (CRI $\geq$ 85). In other embodiments, the second light beam 402 is a continuous light beam in the second time period T12, and the first light beam 401 is a flicker light beam with a flicker frequency in the first time period T11, and the disclosure is not limited thereto. According to some embodiments, a flicker frequency range of the second light beam 402 in the second time period T12 is >0.1 Hz, and preferably 0.1-2000 Hz, but not limited thereto. In the embodiment, the duration of the first time period T11 is equal to the duration of the second time period T12, and the sum of the duration of the first time period T11 and the duration of the second time period T12 is equal to the duration of the first period, that is, the first time period T11 and the second time period T12 respectively account for 50% of the first period T1. In another embodiment, the first time period T11 or the second time period T12 may account for 40-60% of the first period T1, but not limited thereto. When the flicker frequency range of the second light beam 402 is 0.1-2000 Hz, the frequency has exceeded the recognition frequency of the human eye. Therefore, although the second light beam 402 is a flicker light beam, the patient cannot easily perceive the flickering of the beam. In the embodiment, the first light beam 401 generated by the light source device 100 in the first time period T11 of the first period T1 may provide light stimulation of a continuous light beam, and the second light beam 402 generated in the second time period T12 of the first period T1 may provide light stimulation of a flicker light beam.

FIG. 5 is an optical signal timing diagram according to some embodiments of the disclosure. The optical signal timing diagram shown in FIG. 5 is similar to FIG. 4. The first light source 110 provides a first light beam 501 in the first time period T11 of the first period T1, and the second light source 120 is configured to provide a second light beam 502 in the second time period T12 of the first period T1. The first light beam 501 and the second light beam 502 have different light intensities, and the light intensity difference is less than a threshold, for example, less than 10% or less. In addition, the first light beam 501 and the second light beam 502 have the same color temperature and the same spectrum, and are mixed into light with a high color rendering index (CRI $\geq$ 85).

The difference between FIG. 5 and FIG. 4 is that the first light beam 501 in the first time period T11 and the second

light beam 502 in the second time period T12 are both flicker light beams with flicker frequencies, the first light beam 501 has a first flicker frequency, and the second light beam 502 has a second flicker frequency. In an embodiment, the first flicker frequency of the first light beam 501 is different from the second flicker frequency of the second light beam 502. In another embodiment, the first flicker frequency of the first light beam 501 is the same as the second flicker frequency of the second light beam 502, and the disclosure is not limited thereto. According to some embodiments, flicker frequency ranges of the first light beam 501 and the second light beam 502 are respectively >0.1 Hz, and preferably 0.1-2000 Hz, but not limited thereto. According to some embodiments, the first light beam 501 and the second light beam 502 may have the same duty ratio or different duty ratios. According to some embodiments, the duty ratio of the first light beam 501 and the second light beam 502 is 40-60%, and preferably 50%, but not limited thereto. In the embodiment, the first light beam 501 provided by the light source device 100 in the first time period T11 of the first period T1 and the second light beam 502 provided in the second time period T12 of the first period T1 may both provide light stimulation of flicker light beams.

FIG. 6 is an optical signal timing diagram according to some embodiments of the disclosure. The optical signal timing diagram shown in FIG. 5 is similar to FIG. 6. The first light source 110 provides a first light beam 601 in the first time period T11 of the first period T1, and the second light source 120 is configured to provide a second light beam 602 in the second time period T12 of the first period T1. The light intensity difference between the first light beam 601 and the second light beam 602 is less than a threshold, for example, less than 10% or less.

The difference between FIG. 6 and FIG. 5 is that the first light beam 601 and the second light beam 602 have the same color temperature but different spectra. Therefore, in the embodiment, the light beams provided by the light source device 100 in the first period T1 are light beams that have the same color temperature but different spectra in the first period T1 and are emitted alternately to be mixed into light with a high color rendering index (CRI $\geq$ 85) to generate visual stimulation to the patient. Since the first light beam 601 and the second light beam 602 have the same color temperature but different spectra, the first light beam 601 and the second light beam 602 may have different light intensities for different usage purposes. In some embodiments, if the light source device 100 is used as a display, the first light beam 601 and the second light beam 602 may have the same light intensity to prevent the user from seeing a screen with changing brightness. In other embodiments, if the light source device 100 is used to provide illumination, the first light beam 601 and the second light beam 602 may have different light intensities, and the light intensity difference is less than a threshold, for example, less than 10% or less, so that the user receives light stimulation with changes in brightness.

In the embodiments of FIG. 2 to FIG. 6, one of the first light beams 201, 301, 401, 501, and 601 and the second light beams 202, 302, 402, 502, and 602 may be white light or equal energy white light in a wavelength range or have a continuous spectrum in a wavelength range. According to some embodiments, the equal energy white light may be that each wavelength has the same energy in a given wavelength range, for example, all wavelengths have the same energy in a range of 400-800 nm. According to some embodiments, there is a continuous spectrum in a wavelength range, and the energy of each wavelength may be different in a given

wavelength range, for example, all wavelengths have different energies in the range of 400-800 nm.

FIG. 7 is an acousto-optic signal timing diagram according to some embodiments of the disclosure. Please refer to FIG. 1 and FIG. 7 at the same time. According to some embodiments, the light source device **100** further includes a sound source **150** for generating a sound wave pulse **S**. An emission period of the sound wave pulse **S** is the same as the first period **T1**. As shown in FIG. 7, in the first time period **T11** of the first period **T1**, the first light source **110** emits a first light beam **701**, and in the second time period **T12** of the first period **T1**, the second light source **120** emits a second light beam **702**. The first light beam **701** and the second light beam **702** here may be the various embodiments described in FIG. 2 to FIG. 6, so there will be no repetition. The first light beam **701** and the second light beam **702** may also be a combination of other embodiments mentioned below and are not limited thereto. On the other hand, in the first period **T1**, the sound source **150** emits a sound wave pulse **703** with a width **W**. According to some embodiments, the sound wave pulse **703** may be at any position in the first period **T1**, for example, in the first time period **T11**, in the second time period **T12**, or partially in the first time period **T11** and partially in the second time period **T12**. According to some embodiments, the time length of the sound wave pulse **703** is less than the first period **T1**, and preferably 0.1-0.25 **T1**, and the disclosure is not limited thereto. Therefore, in the first period **T1**, there is not only light stimulation of the first light beam **701** and the second light beam **702**, but also sound stimulation generated by the sound wave pulse **703** emitted by the sound source. Therefore, in the first period **T1**, the light source device **100** may provide acousto-optic stimulation at the same time to enhance stimulation to the brain of the user.

FIG. 8A to FIG. 8C are optical signal timing diagrams according to some embodiments of the disclosure. Please refer to FIG. 1 and FIG. 8A to FIG. 8C at the same time. The optical signal timing diagram shown in FIG. 8A is similar to FIG. 2. The first light source **110** provides a first light beam **801** in the first time period **T11** of the first period **T1**, and the second light source **120** is configured to provide a second light beam **802** in the second time period **T12** of the first period **T1**. The first light beam **801** and the second light beam **802** have different light intensities, and the light intensity difference between the two is less than a threshold, for example, less than 10% or less.

As shown in FIG. 1, the light source device **100** further includes a third light source **130** and a fourth light source **140**. The third light source **130** is configured to provide a third light beam **L3**, and the fourth light source is configured to provide a fourth light beam **L4**. The third light source **130** and the fourth light source **140** are similar to the first light source **110** and the second light source **120** and are configured to be emitted alternately to generate light stimulation, and at least one set of the beams (**L1+L2** or **L3+L4**) may be mixed into light with a high color rendering index ($CRI \geq 85$). According to some embodiments, the third light beam **L3** and the fourth light beam **L4** may have different light intensities, and the light intensity difference is less than a threshold, for example, less than 10% or less. According to some embodiments, the third light source **130** and the fourth light source **140** are array light emitting diodes or other elements that may emit similar beams, and the disclosure is not limited thereto. As shown in FIG. 8B, the third light source **130** is configured to provide a third light beam **803** in a third time period **T21** of a second period **T2**. The fourth light source **140** is configured to provide a fourth light beam

804 in a fourth time period **T22** of the second period **T2**, and the third light beam **803** and the fourth light beam **804** are emitted alternately in the second period **T2**. In the embodiment, the duration of the third time period **T21** is equal to the duration of the fourth time period **T22**, and the sum of the duration of the third time period **T21** and the duration of the fourth time period **T22** is equal to the duration of the second period, that is, the third time period **T21** and the fourth time period **T22** respectively account for 50% of the second period **T2**. According to some embodiments, a second frequency **f2** corresponding to the second period **T2** may be different from the first frequency **f1** corresponding to the first period **T1**. According to some embodiments, the second frequency **f2** corresponding to the second period **T2** is 55-65 Hz, that is, $f2=1/T2=55-65$ Hz, as shown in FIG. 8C. According to some embodiments, the second frequency **f2** corresponding to the second period **T2** is 60 Hz, and the disclosure is not limited thereto. According to some embodiments, the duration of the third time period **T21** and the duration of the fourth time period **T22** may be equal or unequal, and the disclosure is not limited thereto.

In the embodiment, the first light beam **801** and the second light beam **802** may be the various embodiments described in FIG. 2 to FIG. 6 or a combination of other embodiments mentioned below and are not limited thereto, so there will be no repetition. The third light beam **803** and the fourth light beam **804** here may be the various embodiments described in FIG. 2 to FIG. 6 or a combination of other embodiments mentioned below and are not limited thereto. In some embodiments, the first light beam **801** and the second light beam **802** have the same first color temperature, and the mixed light of the first light beam **801** and the second light beam **802** has a high color rendering index ($CRI \geq 85$). The third light beam **803** and the fourth light beam **804** have the same second color temperature, and the mixed light of the third light beam **803** and the fourth light beam **804** has a high color rendering index ($CRI \geq 85$). In other embodiments, the mixed light of the first light beam **801** and the second light beam **802** has a high color rendering index (for example, $CRI \geq 85$), but the mixed light of the third light beam **803** and the fourth light beam **804** may not have a high color rendering index (for example, $CRI < 85$). According to some embodiments, the first color temperature and the second color temperature may be the same or different, and the disclosure is not limited thereto. According to some embodiments, when the first color temperature is the same as the second color temperature, the spectra of the first light beam **801**, the second light beam **802**, the third light beam **803**, and the fourth light beam **804** are all different.

When the light source device **100** emits two sets of light with different periods or frequencies at the same time, for example, the first period **T1** and the second period **T2** in FIG. 8A to FIG. 8C, the light source device **100** may perform light stimulation with two different frequencies on the patient, which increases stimulation of the brain of the patient.

FIG. 9 is an optical signal timing diagram according to some embodiments of the disclosure. According to some embodiments, the first light source **110** and the second light source **120** in FIG. 1 may have the same or different phosphor compositions, so two different light beams may be emitted at the same time, for example, a combination of white light and blue light, and the disclosure is not limited thereto. As shown in FIG. 9, in the first time period **T11** of the first period **T1**, a first light beam **901** emitted by the first light source **110** is a combination of white light **901A** and blue light **901B**. In the second time period **T12** of the first

period T1, a second light beam 902 emitted by the second light source 120 is a combination of white light 902A and blue light 902B. According to some embodiments, the light intensity difference between the first light beam 901 and the second light beam 902 is less than a threshold, for example, less than 10% or less. The light intensity of the first light beam 901 is the sum of the light intensities of the white light 901A and the blue light 901B, and the light intensity of the second light beam 902 is the sum of the light intensities of the white light 902A and the blue light 902B. According to some embodiments, the white light 901A of the first light beam 901 and the white light 902A of the second light beam 902 may have the same color temperature and the same or different spectra, and the disclosure is not limited thereto. According to some embodiments, the blue light 901B of the first light beam 901 and the blue light 902B of the second light beam 902 may have the same color temperature and the same or different spectra, and the disclosure is not limited thereto. According to some embodiments, a light intensity ratio of the white light 901A to the blue light 901B in the first light beam 901 may be the same as or different from a light intensity ratio of the white light 902A to the blue light 902B in the second light beam 902, and the disclosure is not limited thereto. The combinations of the white light and the blue light of the first light beam 901 and the second light beam 902 described in the embodiment may be applied to the foregoing embodiments and are not limited thereto.

FIG. 10 is an optical signal timing diagram according to some embodiments of the disclosure. According to some embodiments, the first light source 110 and the second light source 120 in FIG. 1 may have the same or different light source compositions, so a combination of blue light, green light, and red light may be emitted. As shown in FIG. 10, in the first time period T11 of the first period T1, a first light beam 1001 emitted by the first light source 110 is a combination of blue light 1001A, green light 1001B, and red light 1001C. In the second time period T12 of the first period T1, a second light beam 1002 emitted by the second light source 120 is a combination of blue light 1002A, green light 1002B, and red light 1002C. According to some embodiments, the light intensity difference between the first light beam 1001 and the second light beam 1002 is less than a threshold, for example, less than 10% or less. The light intensity of the first light beam 1001 is the sum of the light intensities of the blue light 1001A, the green light 1001B, and the red light 1001C, and the light intensity of the second light beam 1002 is the sum of the light intensities of the blue light 1002A, the green light 1002B, and the red light 1002C. According to some embodiments, the blue light 1001A of the first light beam 1001 and the blue light 1002A of the second light beam 1002 may have the same color temperature and the same or different spectra, and the disclosure is not limited thereto. According to some embodiments, the green light 1001B of the first light beam 1001 and the green light 1002B of the second light beam 1002 may have the same color temperature and the same or different spectra,

and the disclosure is not limited thereto. According to some embodiments, the red light 1001C of the first light beam 1001 and the red light 1002C of the second light beam 1002 may have the same color temperature and the same or different spectra, and the disclosure is not limited thereto. According to some embodiments, a light intensity ratio of the blue light 1001A to the green light 1001B to the red light 1001C in the first light beam 1001 may be the same as or different from a light intensity ratio of the blue light 1002A to the green light 1002B to the red light 1002C in the second light beam 1002, and the disclosure is not limited thereto. The combinations of the blue light, the green light, and the red light of the first light beam 1001 and the second light beam 1002 described in the embodiment may be applied to the foregoing embodiments and are not limited thereto.

FIG. 11 is an optical signal timing diagram according to some embodiments of the disclosure. According to some embodiments, the first light source 110 and the second light source 120 in FIG. 1 respectively emit monochromatic light or white light, wherein when the color of a single light is within 4 MacAdam ellipses in the same x and y coordinate range, there may be different spectra. Therefore, the periodic changes of two different spectra may be used to modulate new light. As shown in FIG. 11, in the first time period T11 of the first period T1, the first light source 110 emits a first light beam 1101, and in the second time period T12 of the first period T1, the second light source 120 emits a second light beam 1102. According to some embodiments, the spectra of the first light beam 1101 and the second light beam 1102 are different, and a color coordinate difference is within 4 MacAdam ellipses. According to some embodiments, when the light source device 100 is applied to a display, the light intensities of the first light beam 1101 and the second light beam 1102 are the same (the light intensity difference is less than 10%). According to some embodiments, when the light source device 100 is applied to external light stimulation, the light intensities of the first light beam 1101 and the second light beam 1102 are different. The combinations of the first light beam 1101 and the second light beam 1102 described in the embodiment may be applied to the foregoing embodiments and are not limited thereto. Regardless of whether the white light is composed of a single light source or dual light sources, the higher the color rendering index, the better the response to the user, especially when CRI>85.

FIG. 12 is a schematic diagram of color coordinate configurations of the same color temperature defined by the American National Standards Institute (ANSI). Please refer to FIG. 12. In the embodiment, the definition of the same color temperature is in accordance with the definition of the ANSI. In other words, for light sources with the same color temperature designed according to the standard, the color difference is not easily perceivable to the human eye. Please refer to Table 1 below for the detailed coordinate values of the color coordinate configurations defined by the ANSI as shown in the schematic diagram of FIG. 12:

TABLE 1

The data range of Table 1 may be converted into tolerance quadrilateral color temperature ranges S1 to S8 in FIG. 12. For example, color temperature coordinate values in the tolerance quadrilateral color temperature range S1 are very close to the human eye, and so on. In more detail, the tolerance quadrilateral in Table 1 may be further converted into the color temperature range as shown in Table 2 below:

TABLE 2

Correlated color temperature (CCT)	Target-related color temperature (K) and tolerance
2700 k	2725 $\pm$ 145
3000 k	3045 $\pm$ 175
3500 k	3465 $\pm$ 245
4000 k	3985 $\pm$ 275
4500 k	4503 $\pm$ 243
5000 k	5028 $\pm$ 283
5700 k	5665 $\pm$ 355
6500 k	6530 $\pm$ 510

The data range of Table 2 may be converted into elliptical color temperature ranges e1 to e8 in FIG. 3. Further, the elliptical color temperature ranges e1 to e8 are also referred to as MacAdam ellipses. For example, color temperature coordinate values fallen within the elliptical color temperature range e1 are very close to the human eye, and so on. It is worth noting that the coordinate data in Table 1 and Table 2 are examples to illustrate that the color temperatures in the embodiment are substantially the same. Please refer to the latest definition of the ANSI for actual coordinate data, and the disclosure is not limited thereto. In another embodiment, having substantially the same color temperature represents being in the same elliptical color temperature range. In this way, the light source device 100 may select light sources with different circadian action factors (CAFs) according to the actual use environment, time, and purpose in the case where the user cannot easily perceive changes in light color temperature to maintain the physiological period of the user, while providing sufficient light source.

FIG. 13A and FIG. 13B are spectral distributions according to some embodiments of the disclosure. As shown in FIG. 13A, a spectrum (A) and a spectrum (B) have the same color temperature. In the embodiment, the color temperature of the spectrum (A) is 5529K, and the color temperature of the spectrum (B) is 5400K, but the spectra have different spectral distributions. The intensity peak of the spectrum (A) is approximately at a wavelength of 450 nm, and the intensity peak of the spectrum (B) is approximately at a wavelength of 460 nm. The color rendering index of the spectrum (A) is 81, the color rendering index of the spectrum (B) is 86, and the color rendering index of the spectrum (A) and the spectrum (B) after mixing is 86. As shown in FIG. 13A, a CAF range of the spectrum (A) is CAF=0.65-0.75 and a CAF range of the spectrum (B) is CAF=0.85-

0.95. Therefore, in the case of the same color temperature, light with different spectra have different CAFs.

As shown in FIG. 13B, the two spectra in the drawing are respectively the spectrum (A) and a spectrum (C). The color temperature of the spectrum (C) is 4919K, and the spectrum (C) is a full spectrum in a wavelength range of 400-7000 nm, so the color rendering index of the spectrum (C) is 97. The color rendering index of the spectrum (A) and the spectrum (C) after mixing is 90.

FIG. 14A and FIG. 14B show a relationship between a color rendering index and an electroencephalography (EEG) signal according to some embodiments of the disclosure. FIG. 14A uses a single light source to flicker at a fixed flicker frequency. In the embodiment, the flicker frequency is 40 Hz to measure the signal intensity of the EEG at 40 Hz in different color rendering indexes. In FIG. 14A, the color temperature of a light source is around 5000K. When the color rendering index of the light source gradually increases from 60 to close to 100, the signal of the EEG at 40 Hz is also correspondingly enhanced, which means that the higher the color rendering index of the light source, the better the response to the user, especially when the color rendering index, CRI $\geq$ 85, the signal intensity is above 4, which means that the signal intensity is more significant than when the color rendering index, CRI<85.

FIG. 14B is similar to FIG. 14A, but FIG. 14B uses dual light sources to flicker alternately at a fixed flicker frequency. In the embodiment, the flicker frequency is 40 Hz to measure the signal intensity of the EEG at 40 Hz. As shown in FIG. 14B, when the color rendering index of the light source is less than 85, the signal (0.86-0.99) of the EEG at 40 Hz is significantly less than the signal (>1.79) of the EEG at 40 Hz when the color rendering index of the light source is greater than 85, which means that the higher the color rendering index of the light source, the better the response to the user. It can be seen from FIG. 14B that when the color rendering index, CRI $\geq$ 85, the signal intensity is above 1.5, which means that the signal intensity is more significant than when the color rendering index, CRI<85.

In FIG. 14A and FIG. 14B, when CRI $\geq$ 85, the EEG signal intensity (>4) of FIG. 14A is stronger than the EEG signal intensity (1.79-2.98) of FIG. 14B. Since FIG. 14A uses the single light source to flicker, the brightness difference is more obvious, and the obtained EEG signal is stronger. In FIG. 14B, since the dual light sources are used to flicker alternately, the brightness difference is less obvious, and the obtained EEG signal is weaker than the EEG signal when the single light source flickers (as shown in FIG. 14A). However, in actual use, when using a single light source to flicker, since the brightness contrast is more obvious, there is a greater burden on the eyes of the user. When using dual light sources to flicker, since the brightness change is smaller, there is hardly any burden on the eyes of the user, which is more suitable for integration into the daily life environment.

FIG. 15A to FIG. 15B are optical signal timing diagrams according to some embodiments of the disclosure. According to some embodiments, a single display pixel in the first light source 110 and the second light source 120 in FIG. 1 has periodic changes of different monochromatic light combinations. At this time, the single display pixel may have two different change combinations, such as emitting different monochromatic light at the same time or sequentially emitting different monochromatic light. As shown in FIG. 15A, in the first time period T11 of the first period T1, the first light source 110 emits red light 1201A, green light 1201B, and blue light 1201C at the same time. In the second time period T12 of the first period T1, the second light source 120 emits red light 1202A, green light 1202B, and blue light 1202C at the same time. As shown in FIG. 15B, in a first part T11A, a second part T11B, and a third part T11C of the first time period T11 of the first period T1, the first light source 110 sequentially emits red light 1211A, green light 1211B, and blue light 1211C. In a first part T12A, a second part T12B, and a third part T12C of the second time period T12 of the first period T1, the second light source 120 sequentially emits red light 1212A, green light 1212B, and blue light 1212C. According to some embodiments, the wavelengths of the red light 1211A and the red light 1212B are different, and the color coordinate difference may be within 4 MacAdam ellipses. According to some embodiments, the wavelengths of the green light 1211B and the green light 1212B are different, and the color coordinate difference may be within 4 MacAdam ellipses. According to some embodiments, the wavelengths of the blue light 1211C and the blue light 1212C are different, and the color coordinate difference may be within 4 MacAdam ellipses. According to some embodiments, when the light source device 100 is applied to a display, the light intensities of a first light beam 1201 and a second light beam 1202 are the same. According to some embodiments, when the light source device 100 is applied to external light stimulation, the light intensities of the first light beam 1201 and the second light beam 1202 are different. The combinations of the first light beam 1201 and the second light beam 1202 described in the embodiment may be applied to the foregoing embodiments and are not limited thereto.

FIG. 16 is a schematic diagram of a display device according to some embodiments of the disclosure. Please refer to FIG. 16. A display device 1300 of the embodiment includes a backlight element 1310 and a display 1320. The display 1320 may be a liquid crystal display panel or other suitable spatial light modulators. The backlight element 1310 may be the various embodiments of the light source device 100 described above and is configured to provide backlight of the display 1320. According to some embodiments, the backlight element 1310 is a direct-type backlight element or an edge-type backlight element, and the disclosure is not limited thereto. When the backlight element 1310 includes the various embodiments of the light source device 100 described above, a light period of the backlight of the display is composed of two different light. Therefore, when the user uses the display, light stimulation may be received at the same time. In another embodiment, a light source of the display device is a light emitting unit of the display, and light emitted by each light emitting unit is alternately emitted in the time of one period as described the foregoing embodiments.

FIG. 17 is a schematic diagram of a display device according to some embodiments of the disclosure. As shown in FIG. 17, a display device 1400 has a light source device 1410. The light source device 1410 is similar to the light

source device 100 in FIG. 1 and may emit two different light alternately in one period. In the embodiment, a light beam emitted by the light source device 1410 is infrared light.

In some embodiments, the light source device or the display device described above may be further combined with an eye movement sensor to track the movement of an eye portion E of the user. The light source device 1410 may generate the infrared light with a flicker frequency of 40 Hz corresponding to the first period to provide stimulation of the infrared light or other invisible light with a flicker frequency of 40 Hz around the line of sight of the user.

FIG. 18 is a schematic diagram of a light source device according to some embodiments of the disclosure. The light source device 100B shown in FIG. 18 is similar to the light source device 100 shown in FIG. 1. The difference between the light source device 100B shown in FIG. 18 and the light source 100 shown in FIG. 1 is that, the light source device 100B further includes a signal monitor 160. The signal monitor 160 connects to the first light source 110, the second light source 120, the third light source 130, the fourth light source 140 and the sound device 150.

In some embodiments, the signal monitor 160 monitor a characteristic signal or a variation of the characteristic signal of the first light source 110 is above a first threshold. In some embodiments, when the signal monitor 160 detects that the characteristic signal or the variation of the characteristic signal of the first light source 110, the signal monitor 160 turns on the sound device 150 to provide a sound wave pulse S.

In some embodiments, the signal monitor 160 monitor a characteristic signal or a variation of the characteristic signal of the sound device 150 is above a second threshold. In some embodiments, when the signal monitor 160 detects that the characteristic signal or the variation of the characteristic signal of the sound device 150, the signal monitor 160 turns on the first light source 110 to provide a first light beam 110.

In some embodiments, the characteristic signal of the first light source 110 includes, but is not limited to, a current input to the first light source 110, a voltage input to the first light source 110, or a light intensity of the first light beam L1. The current and/or the voltage, or the variations of the current and/or the voltage input to the first light source 110 indicates that the first light source 110 being turned on, and generating a first light beam L1. The light intensity of the first light beam L1 indicates that the first light beam L1 has been generated, and not a random background noise.

In some embodiments, the characteristic signal of the sound device 150 includes, but is not limited to, a current input to the sound device 150, a voltage input to the sound device 150, or a sound intensity of the sound device 150. The current and/or the voltage, or the variations of the current and/or the voltage input to the sound device 150 indicates that the sound device 150 being turned on, and generating a sound wave pulse S. The sound intensity of the sound wave pulse S indicates that the sound wave pulse S has been generated, and not a random background noise.

In some embodiments, the signal monitor 160 may be, but not limited to, a voltage meter, a current meter, a light detector, and/or a sound detector.

FIG. 19 is an acousto-optic signal timing diagram according to some embodiments of the disclosure. Please refer to FIG. 18 and FIG. 19 at the same time. As shown in FIG. 19, in the first time period T11 of the first period T1, the first light source 110 emits a first light beam 1901. The first light beam 1901 has similar characteristics as the first light beam

201 in FIG. 2 and the first light beam 301 in FIG. 3. Thus, the characteristics of the first light beam 1901 is not repeated here.

When the signal monitor 160 detects the first characteristic signal or a variation of the first characteristic signal of the first light source 110 is larger than a first threshold, such as current input to the first light source 110, a voltage input to the first light source 110, or a light intensity of the first light beam L1, is larger than a first threshold, the signal monitor 160 drives the sound device 150 to output the sound wave pulse 1903 in a second time period of the first period T1. An emission period of the sound wave pulse S is the same as the first period T1, as shown in FIG. 19. As a result, when there is a first light beam 1901 being generated, the sound device 150 is triggered and generates a sound wave pulse 1903 after the first light beam 1901. The location of the sound wave pulse 1903 can be anywhere within the first time period, which is not limited thereto.

FIG. 20 is an acousto-optic signal timing diagram according to some embodiments of the disclosure. The acousto-optic signal timing diagram shown in FIG. 20 is similar to the acousto-optic signal timing diagram shown in FIG. 19. The difference is that, in FIG. 20, the first light beam 2001 is a flicker light beam. In some embodiments, a flicker frequency of the range of the flicker light beam 2001 is 0.1-2000 Hz.

FIG. 21 is an acousto-optic signal timing diagram according to some embodiments of the disclosure. The acousto-optic signal timing diagram shown in FIG. 21 is similar to the acousto-optic signal timing diagram shown in FIG. 19. The difference is that, in FIG. 21, the sound device 150 emits a sound wave pulse 2103 in a second time period of the first period T1. The sound wave pulse 2103 has similar characteristics as the sound wave pulse 703 in FIG. 7. Thus, the characteristics of the sound wave pulse 2103 is not repeated here.

When the signal monitor 160 detects the second characteristic signal or a variation of the second characteristic signal of the sound device 150 is larger than a second threshold, such as current input to the sound device 150, a voltage input to the sound device 150, or a sound intensity of the sound wave pulse 2103, is larger than a second threshold, the signal monitor 160 drives the first light source 110 to output the first light beam 2101 in a first time period T11 of the first period T1. As a result, when there is a sound wave pulse 2113 being generated, the first light source 110 is triggered and generates a first light beam 2101 after the sound wave pulse 2103.

FIG. 22 is an acousto-optic signal timing diagram according to some embodiments of the disclosure. The acousto-optic signal timing diagram shown in FIG. 22 is similar to the acousto-optic signal timing diagram shown in FIG. 21. The difference is that, in FIG. 20, the first light beam 2201 is a flicker light beam. In some embodiments, a flicker frequency of the range of the flicker light beam 2001 is 0.1-2000 Hz.

FIG. 23 is an acousto-optic signal timing diagram according to some embodiments of the disclosure. The acousto-optic signal timing diagram shown in FIG. 23 is similar to the acousto-optic signal timing diagram shown in FIG. 19. The difference is that, in FIG. 23, besides the first light beam 2301 emitted by the first light source 110, the sound wave pulse 2303 emitted by the sound device, the light source device 100B also includes a second light source, providing a second light beam 2302 in a time period T12 of the first period T1. The first light beam 2301 and the second light beam 2302 are similar to the first light beam 201 and the

second light beam 202 shown in FIG. 2, first light beam 301 and the second light beam 302 shown in FIG. 3. Thus, the characteristics of the first light beam 2301 and the second light beam 2302 is not repeated here.

5 In some embodiments, the color temperature and the spectrum of the first light beam 2301 and the second light beam 2302 are the same, and there is only difference in light intensities, the first light beam 2301 and the second light beam 2302 emitted by the light source device 100B respectively flicker with different light intensities but the same first frequency f1 to provide light stimulation, and the mixed light of the first light beam 2301 and the second light beam 2302 has a high color rendering index (CRI), that is, CRI $\geq$ 85. Since the difference between the light intensities of 10 the first light beam 2301 and the second light beam 2302 is only less than the threshold, for example, the difference between the light intensities of the first light beam 2301 and the second light beam 2302 is less than 10% or less, for a patient to be treated, the received light intensity change is 15 relatively small, which can reduce the burden on the eyes of the patient. By changing an irradiation period of the first light beam 2301 and the second light beam 2302 emitted by the first light source 110 and the second light source 120 in the light source device 100B, light stimulation received by 20 the patient may be adjusted, for example, when f1=35-45 Hz, thereby inducing gamma brain waves to activate microglia. In subsequent embodiments, various implementations 25 will be explained one by one.

FIG. 24 is an acousto-optic signal timing diagram according to some embodiments of the disclosure. The acousto-optic signal timing diagram shown in FIG. 24 is similar to the acousto-optic signal timing diagram shown in FIG. 23. The difference is that, in FIG. 24, the second light beam 2402 is a flicker light beam. In some embodiments, a flicker 30 frequency of the range of the flicker light beam 2402 is 0.1-2000 Hz. The first light beam 2401 and the second light beam 2402 are similar to the first light beam 401 and the second light beam 402 shown in FIG. 4. Thus, the characteristics of the first light beam 2401 and the second light beam 2402 is not repeated here.

FIG. 25 is an acousto-optic signal timing diagram according to some embodiments of the disclosure. The acousto-optic signal timing diagram shown in FIG. 25 is similar to the acousto-optic signal timing diagram shown in FIG. 23. The difference is that, in FIG. 25, the first light beam 2501 and the second light beam 2502 are both flicker light beams. In some embodiments, a flicker frequency of the range of the flicker first light beam 2501 and the flicker second light beam 2502 is 0.1-2000 Hz. The first light beam 2501 and the second light beam 2502 are similar to the first light beam 501 and the second light beam 502 shown in FIG. 5. Thus, the characteristics of the first light beam 2501 and the second light beam 2502 is not repeated here.

FIG. 26 is an acousto-optic signal timing diagram according to some embodiments of the disclosure. The acousto-optic signal timing diagram shown in FIG. 26 is similar to the acousto-optic signal timing diagram shown in FIG. 21. The difference is that, in FIG. 26, the sound device 150 emits a sound wave pulse 2603 in a second time period of the first period T1. The sound wave pulse 2603 has similar characteristics as the sound wave pulse 703 in FIG. 7 and the sound wave pulse 2103 in FIG. 21. Thus, the characteristics of the sound wave pulse 2603 is not repeated here.

When the signal monitor 160 detects the second characteristic signal or a variation of the second characteristic signal of the sound device 150 is larger than a second threshold, such as current input to the sound device 150, a

voltage input to the sound device 150, or a sound intensity of the sound wave pulse 2603, is larger than a second threshold, the signal monitor 160 drives the first light source 110 to output the first light beam 2601 in a first time period T11 of the first period T1. As a result, when there is a sound wave pulse 2613 being generated, the first light source 110 is triggered and generates a first light beam 2601 after the sound wave pulse 2603.

FIG. 27 is an acousto-optic signal timing diagram according to some embodiments of the disclosure. The acousto-optic signal timing diagram shown in FIG. 27 is similar to the acousto-optic signal timing diagram shown in FIG. 26. The difference is that, in FIG. 27, the second light beam 2702 is a flicker light beam. In some embodiments, a flicker frequency of the range of the flicker light beam 2702 is 0.1-2000 Hz. The first light beam 2701 and the second light beam 2702 are similar to the first light beam 401 and the second light beam 402 shown in FIG. 4, and the first light beam 2401 and the second light beam 2402 shown in FIG. 24. Thus, the characteristics of the first light beam 2701 and the second light beam 2702 is not repeated here.

FIG. 28 is an acousto-optic signal timing diagram according to some embodiments of the disclosure. The acousto-optic signal timing diagram shown in FIG. 28 is similar to the acousto-optic signal timing diagram shown in FIG. 26. The difference is that, in FIG. 28, the first light beam 2801 and the second light beam 2802 are both flicker light beams. In some embodiments, a flicker frequency of the range of the flicker first light beam 2801 and the flicker second light beam 2802 is 0.1-2000 Hz. The first light beam 2801 and the second light beam 2802 are similar to the first light beam 501 and the second light beam 502 shown in FIG. 5, and the first light beam 2501 and the second light beam 2502 shown in FIG. 25. Thus, the characteristics of the first light beam 2801 and the second light beam 2802 is not repeated here.

In summary, the disclosure uses a combination of two or more light to be emitted alternately in the time of one period to provide light stimulation with therapeutic effects. The combination of different forms of light can effectively provide a variety of treatment measures.

What is claimed is:

1. A light source device, comprising:
a first light source, providing a first light beam in a first

time period of a first period; and

a second light source, providing a second light beam in a

second time period of the first period, wherein

the first light beam and the second light beam are emitted
alternately in the first period, and wherein at least one
of the first light beam in the first time period and the
second light beam in the second time period is a flicker
light beam,

wherein the first light beam in the first time period and the
second light beam in the second time period are both
flicker light beams, and a first flicker frequency of the
first light beam is different from a second flicker
frequency of the second light beam.

2. The light source device according to claim 1, wherein
a color rendering index of mixed light of the first light beam
and the second light beam is greater than or equal to 85.

3. The light source device according to claim 1, wherein
the first light beam and the second light beam have different
spectra.

4. The light source device according to claim 3, wherein
the first light beam and the second light beam have a same
color temperature.

5. The light source device according to claim 1, wherein
a flicker frequency range of the flicker light beam is 0.1-
2000 Hz.

6. The light source device according to claim 1, wherein
the first time period and the second time period have the
same or different lengths.

7. A light source device, comprising:
a first light source, providing a first light beam in a first
time period of a first period;
a sound device, providing a sound wave pulse in a second
time period of the first period; and
a signal monitor, connecting to the first light source and
the sound device, and monitoring a first characteristic
signal of the first light source or a second characteristic
signal of the sound device,

wherein when the signal monitor detects the first charac-
teristic signal or a variation of the first characteristic
signal is larger than a first threshold, drive the sound
device to output the sound wave pulse in the second
time period,

wherein when the signal monitor detects the second charac-
teristic signal or a variation of the second charac-
teristic signal is larger than a second threshold, drive
the first light source to output the first light beam in the
first time period.

8. The light source device according to claim 7, wherein
the first characteristic signal includes: a current input to the
first light source, a voltage input to the first light source, or
a light intensity of the first light beam.

9. The light source device according to claim 7, wherein
the second characteristic signal includes: a current input to
the sound device, a voltage input to the sound device, or a
sound intensity of the sound wave pulse.

10. The light source device according to claim 7, the first
light beam is a monochromatic light beam or a white light,
wherein when the first light beam is the white light, a color
rendering index of the first light beam is greater than or
equal to 85.

11. The light source device according to claim 7, wherein
the first light beam is a flicker light beam, wherein a flicker
frequency range of the flicker light beam is 0.1-2000 Hz.

12. The light source device according to claim 7, further
comprising:

a second light source, providing a second light beam in a
third time period of the first period, wherein the third
time period is different from the first time period.

13. The light source device according to claim 7, wherein
a color rendering index of mixed light of the first light beam
and the second light beam is greater than or equal to 85.

14. The light source device according to claim 13, wherein
at least one of the first light beam in the first time
period and the second light beam in the third time period
is a flicker light beam, wherein a flicker frequency range of the
flicker light beam is 0.1-2000 Hz.

15. A light source device, comprising:
a first light source, providing a first light beam in a first
time period of a first period;

a second light source, providing a second light beam in a
second time period of a first period;

a sound device, providing a sound wave pulse in a third
time period of the first period; and

a signal monitor, connecting to the first light source and
the sound device, and monitoring a first characteristic
signal of the first light source, a second characteristic
signal of the sound device,

wherein the first light beam and the second light beam are
emitted alternately in the first period,

19

wherein when the signal monitor detects the first characteristic signal or a variation of the first characteristic signal is larger than a first threshold, drive the sound device to output the sound wave pulse in the second time period,

5

wherein when the signal monitor detects the second characteristic signal or a variation of the second characteristic signal is larger than a second threshold, drive the first light source to output the first light beam in the first time period.

10

16. The light source device according to claim **15**, wherein the first characteristic signal includes: a current input to the first light source, a voltage input to the first light source, or a light intensity of the first light beam, wherein the second characteristic signal includes: a current input to the sound device, a voltage input to the sound device, or a sound intensity of the sound wave pulse.

17. The light source device according to claim **15**, wherein a color rendering index of mixed light of the first light beam and the second light beam is greater than or equal to 85.

18. The light source device according to claim **15**, wherein at least one of the first light beam in the first time period and the second light beam in the second time period is a flicker light beam, wherein a flicker frequency range of the flicker light beam is 0.1-2000 Hz.

19. The light source device according to claim **15**, wherein the first light beam and the second light beam have different light intensities, wherein a light intensity difference between the first light beam and the second light beam is less than 10%.
